UNITED STATES PATENT OFFICE

2,512,884

GLUE CONTROL FOR BAG SEALING MACHINES

Helmer Anderson, Minneapolis, Minn., assignor to General Mills, Inc., a corporation of Delaware

Application August 9, 1946, Serial No. 689,618

6 Claims. (Cl. 91—44)

1. An object of this invention is to provide means for automatically shutting off the flow of liquid glue to a bag sealing machine of the type shown and described in my Patent No. 2,257,777, granted October 7, 1941, should the machine for any reason, such as the breaking of a shear pin, stop in a glue-feeding position. This stops application of glue to the bag instantly, thus preventing glue, in such event, from running into the top of the bag and spoiling both bag and contents, and messing up the machine generally.

Another object is the provision of means for automatically returning these parts of the glue feeding mechanism to their normal operating conditions when the sealing machine again resumes its normal operation as by replacing the broken shear pin with a new one.

These and other objects as may hereinafter appear are accomplished by this invention which is fully described in the following specification and shown in the accompanying drawings in which:

Figure 1 is a diagrammatic perspective partly in section showing the portion of the main drive shaft with a fly-ball governor controlling the glue feeding mechanism;

Fig. 2 is a view similar to Fig. 47 of the above Anderson patent; and

Fig. 3 is a copy of Fig. 67 of the above mentioned patent.

The above drawings show a modification of or an addition to the sealer of my Patent No. 2,257,777, granted October 7, 1941. Except for these changes the two machines are identical. Numerals used herein above 600 are applied to similarly numbered parts in the above patent.

In the accompanying drawings Fig. 1 shows a governor-controlled mechanism G driven from the main drive shaft E of the sealer as will later be described which operates to close a micro-switch S to cause glue to be fed at pre-determined intervals by the gluing mechanism so long as the shaft E continues to rotate at its normal rate.

Thus, the shaft E (Fig. 2 of the above patent) is driven by a belt E' running over a pulley 10 journaled on the shaft E, the pulley driving the shaft through a shear pin 12 and a collar 14 keyed on the shaft. This shear pin breaks at intervals due to any overload on the machine. If the glue feeding mechanism of this patent is in a position to feed glue when this occurs, the operator must shut it off at once or damage may result. The present mechanism for shutting off the flow of glue in such an event will now be described.

2. A gear 20 keyed on the shaft E meshes with a gear 22 keyed on a shaft 24 suitably journaled in the ends of a housing 30 which is bolted to a supporting bracket 31 bolted to the main frame of the machine and which together with a cover 33 bolted thereto enclose a fly-ball governor which comprises a collar 32 secured on the shaft 24 and having two opposed fly-ball bell-crank 34 hingedly mounted thereon at 36 with the small arms 38 bearing on opposite sides of a collar 40 which is slidable on the shaft 24 and has a spring 41 pressing the collar 40 to the left tending to fold the bell-crank 34 inwardly. This happens as the shafts E and 24 come to rest.
3. A pin 42 is axially slidable in the hollow end of the shaft 24 and has a crossbar 44 secured thereto at the inner end and having its ends extending through the collar 40 while the center moves through a slot 45 in the shaft 24. The pin 42 bears against a lever 50 clamped on a rocker shaft 52 journaled in bearings 54 on the cover 33. A lever 56 secured on the shaft 52 and a spring 58 keep the lever 50 in contact with the pin 42. A lever 60 at the opposite end of the shaft 52 bears against a roller 62 on the rocker arm of a micro-switch S which receives electric energy from a power-line L and connects through the switch mechanism (not shown) with the line 64 to a solenoid 66.
4. With the parts in the positions shown the governor arms are separated showing the shaft E in normal operation and the pin 42 moved to the right moving the switch arm with the roller 62 to a position closing the switch S and energizing the solenoid 66 whose core 68 is connected to one end of a lever 70 fulcrumed at 72 while the other end operates an air valve 764 (see Fig. 47 of Anderson Patent No. 2,257,777) which has upper and lower valve faces adapted to close either valve seat 765 or valve seat 766. A pipe 760 connects to a source of air pressure while a pipe 762 connects through a chamber 761 with apparatus shown in Figs. 58 to 67 of the above Anderson patent including pipes 827 and 825 of Fig. 3 for utilizing this air pressure for operating the glue nozzles of which only one, 670, is shown in Fig. 3.
5. So long as shaft E remains in normal operation the valve 764 will remain in the position shown in Fig. 2 feeding air from the pipe 760 to pipe 762 and maintaining the glue valves in their normal operation. Should the main drive shaft E stop for any reason, such as breaking the shear pin 12, the micro-switch S will break the connection between the line L and the solenoid 66, de-

3

energizing the solenoid and permitting the spring 71 to draw the core 68 down and to lift the valve 764 closing the seat 765 and cutting off air pressure from the pipe 760 to the glue nozzles so that the flow of glue is stopped.

Starting up the shaft E will again cause the governor to close the switch S again energizing the solenoid 66 and opening the valve 764 so as once more to cause the glue nozzles of Anderson Patent No. 2,257,777 to perform their accustomed functions as therein explained.

Thus, it will be seen that I have provided a very simple and efficient means for controlling the mechanism for feeding glue to the bags as they pass through the machine.

While I have shown and described but a single embodiment of my invention, it is to be understood that it is capable of many modifications. Changes, therefore, may be made which do not depart from the spirit and scope of my invention as disclosed in the appended claims.

I claim as my invention:

1. A glue feeding control for a bag closing and sealing machine comprising a glue applying device, a valve controlled air pressure means operatively connected to the glue applying device to control the flow of glue, a solenoid operatively associated with the valve to open and close same, a switch for controlling the electrical power supply to the solenoid, and a governor operably connected to a moving element of the machine and operably associated with the switch to operate same at predetermined speeds of the machine to cause the solenoid to operate the air valve to start and stop the flow of glue at said predetermined speeds.

2. A glue feeding control for bag closing and sealing machine having a sealing means including a glue applying device with an air supply line to cause the glue to feed, the control comprising a valve in the air supply line, a solenoid operatively connected to the valve, a switch connected to the solenoid to control same, and a fly ball governor mounted on a shaft of the sealing machine and operably associated with the switch to operate same at predetermined speeds to cause the solenoid to open and close the air valve controlling glue application.

3. A glue feeding control for a bag closing and sealing machine including a drive shaft driving the machine, and a glue applying device, the control comprising a valve controlled air supply connected to the glue applying device to cause the glue to feed, a solenoid operatively connected to the air supply valve, a switch in circuit with the solenoid to control the power supply thereto, and control means operably associated with the drive shaft and responsive to speed changes thereof

operably associated with the switch to operate the switch at predetermined speeds to open or close the control valve starting or stopping the glue feed.

5. A glue feeding control for a bag closing and sealing machine including a drive shaft and an air supply line leading to a glue applying unit, the control comprising a valve in the air supply line for controlling the air to start and stop the glue feed, a solenoid connected to the valve, a switch in circuit with the solenoid to control the power supply thereto, and governor means mounted on the drive shaft and operably connected to the switch to operate same responsive to speed drops causing the solenoid to operate the air valve to turn off the glue supply when the machine slows below a predetermined speed.

15. A glue feeding control for a bag closing and sealing machine comprising a glue applying device, a valve controlled air supply connected to the glue applying device to cause the flow of glue with air pressure, electrical control means operatively associated with the air supply valve to open and close same thereby controlling the glue application, and a speed responsive governor operably connected to a moving machine element and operatively associated with the electrical control means to bring the control means into operation to close the air valve when the speed drops below a predetermined level to stop the feeding of glue.

25. A glue feeding control for a bag closing and sealing machine comprising a glue applying device, a valve controlled air supply connected to the glue applying device to cause the flow of glue with air pressure, a speed responsive device operably connected to a moving machine element, and a control means operably connected between the speed responsive device and the air supply valve, said control means closing the air valve responsive to a signal from the speed responsive device when the speed drops below a predetermined level to stop the flow of glue.

30. HELMER ANDERSON.
